United States Patent Office.

BENJAMIN CARTER, OF MIDDLETOWN, CONNECTICUT.

Letters Patent No. 90,923, dated June 8, 1869.

IMPROVEMENT IN BOSOM-PADS.

The Schedule referred to in these Letters Patent and making part of the same.

To all whom it may concern:

Be it known that I, BENJAMIN CARTER, of Middletown, county of Middlesex, and State of Connecticut, have invented an Improved Dress Bosom-Pad; and I do hereby declare the same to be fully described in the following specifications, and represented in the accompanying drawings, of which—

Figure 1 is a perspective view of the spring-frame, with the elastic cord attached.

Figure 2 is a perspective view with padding attached.

Figure 3 is a view as applied to the person.

Figure 4 is a sectional view.

Figure 5 is a clasp for securing the springs together in the centre.

The object of my invention is to make a bosom-pad that shall be adjustable, light, and comfortable; and to that end,

It consists of an adjustable spring-frame, around the base of which is arranged an elastic cord, which connects together the several ribs of which it is formed, and provides for its expansion and contraction. The outer surface of this frame is covered with padding of suitable material.

To enable others skilled in the art to make and use my invention, I will proceed to describe the construction and operation thereof.

In making my bosom-pad, I use three or more light elastic springs, *a a*, of steel or other material, of suit-

able length, and bent to the desired form, which are secured together at the centre by a clasp or rivet.

At each end of the springs *a a a*, an eye, *e e*, is formed, by bending the wire, or by attaching a clasp with an eye, through which an elastic cord, *D*, is passed, and secured together at the ends, so as to produce any desired fulness.

By shortening the cord, the fulness is increased, by lengthening, the fulness is diminished. Or the same result may be produced by attaching the elastic cord to the ends of the springs and crossing at the centre, the frame-work being covered with muslin or other elastic material, and filled with curled hair.

The operation and advantage of my bosom-pad over common pads are its adjustability to particular cuts of dress, which are often numerous to every wearer, its lightness, and the entire relief from heat and perspiration occasioned by the common pads.

What I claim, and desire to secure by Letters Patent, is—

An adjustable spring supporting-frame for bosom-pads, consisting of the springs *a*, eyes *e*, and elastic cord *D*, combined substantially as described and for the purpose set forth.

BENJ. CARTER.
